UNITED STATES PATENT OFFICE.

ALFRED H. HUMPHREY, OF NEW YORK, N. Y.

GAS-LAMP.

1,097,719.

Specification of Letters Patent. Patented May 26, 1914.

Application filed July 18, 1913. Serial No. 779,706.

To all whom it may concern:

Be it known that I, ALFRED H. HUMPHREY, a citizen of the United States, residing at New York, N. Y., have invented certain new and useful Improvements in Gas-Lamps, of which the following is a specification.

This invention relates to improvements in gas lamps.

My invention relates particularly to improvements in gas lamps of the indirect type or semi-indirect type, as they are sometimes called; that is, gas lamps in which the light is reflected upwardly from an opaque or semi-opaque or translucent globe closing the lower part of the lamp.

The main objects of this invention are: First, to provide an improved gas lamp of the indirect type. Second, to provide an improved gas lamp of the indirect type where the bowl or globe is closed beneath and open at its top and the parts so arranged that the light rays reflected upwardly and outwardly from the inner surface of the bowl will be practically shadowless. Third, to provide an improved indirect gas lamp in which the operating parts are so arranged as to be entirely out of the path of the products of combustion. Fourth, to provide an improved gas lamp of the indirect type in which the parts are so arranged that the products of combustion escape without unduly heating any portion of the lamp, and at the same time do not interfere with the air supply to the burner, the air being effectively delivered to the mixing tube and to the burner at the point of combustion. Fifth, to provide an improved gas lamp of the indirect type, which is very easily cared for,—that is, the globe is accessible for cleaning and the mantle and burner parts are all fully accessible.

Further objects, and objects relating to structural details, will definitely appear from the detailed description to follow.

45 I accomplish the objects of my invention by the devices and means described in the following specification.

The invention is clearly defined and pointed out in the claims.

50 A structure which is a preferred embodiment of my invention is clearly illustrated in the accompanying drawing forming a part of this specification, in which:

Figure I is a perspective view of my improved gas lamp. Fig. II is a detail top per-

spective view, with the globe holder and globe removed. Fig. III is a similar detail perspective view, from the under side, with the globe holder open. Fig. IV is a detail vertical section through the pilot valve casing. Fig. V is a detail vertical section on a line corresponding to line 5—5 of Fig. IV. Fig. VI is an enlarged detail vertical section through the burner valve casing and parts of the burner. Fig. VII is an enlarged detail section through the hinge of the globe holder. Fig. VIII is a detail plan view of the upper part of the lamp. Fig. IX is a detail vertical section on a line corresponding to line 9—9 of Fig. VIII. Fig. 70 X is a detail vertical section through the globe holder latch.

In the drawing similar reference characters refer to similar parts throughout the several views, and the sectional views are 75 taken looking in the direction of the little arrows at the ends of the section lines.

Referring to the lettered parts of the drawing, the supply pipe 1 is adapted as a support for the lamp. I provide a skeleton 80 frame consisting in the structure illustrated of the coupling or top member 2 having arms 3 thereon. Depending from these arms 3 are side members or hangers 4, 5 and 6; the hangers 4 and 5 being adapted as gas delivery conduits; the hanger 6 being a dummy. The side members or hangers diverge downwardly and are uniformly spaced. At the upper ends of the hangers is an ornamental member 7 which is held in place by the members 8 sleeved upon the side members or hangers and secured to support the member 7 by means of set screws 9.

The burner valve casing 10 and the pilot valve casing 11 are adapted as coupling 95 members for connecting the hangers 4 and 5 respectively to the supporting ring 12. The pilot valve casing 11 is of the same shape as the coupling member 13, the main valve casing being modified in shape only as is necessary to perform its functions.

The main burner valve 14 is of the rotary type. The valve actuating mechanism is an adaptation of that shown in my Re-issue Patent, No. 13,552, dated April 1st 105 1912, and as it forms no part of my present invention, I do not describe the same in detail herein.

In the valve casing 10, below the valve 14, is a gas nozzle valve casing 15 communi- 110

cating with the gas passage of the main valve casing and having a nozzle 16 thereon. The regulating valve 17 for the nozzle is disposed below the valve 14 as shown in Fig. 5 VI, and parallel therewith. The valve casing 10 is provided with a nipple 18 for the mixing tube 19.

The burner 20 is of the inverted type and is provided with a horizontally disposed inlet passage member 21 adapted to receive the horizontally disposed mixing tube 19. To assist in supporting the burner and to prevent its rotation on the mixing tube I provide a rod-like supporting arm 22, which 15 is carried by the perforated downwardly projecting ear 23 on the under side of the valve casing 10, the burner passage member 21 being provided with a downwardly projecting ear 24 adapted to slidably engage 20 this supporting arm. The burner is thus effectively supported in a manner that permits its being freely removed as occasion requires. The pilot 25 is mounted on the valve casing 11 and projects into a suitable 25 proximity to the burner. The pilot flame is regulated by means of the valve 26. See Fig. IV. The ring 12 is formed of a strip of iron, its ends being secured to the valve casing 10 on opposite sides of the nozzle 30 valve casing by means of the screws 27. See Fig. III. The globe 28 is suitably supported in the globe holder 29 which is mounted on the ring 12 by means of the hinge 30. This hinge is disposed opposite 35 to the valve casing 10 so that the globe swings away from the parts of the lamp which require cleaning and adjustment. The globe swings entirely clear so that the burners are freely accessible for adjustment 40 or renewal of the mantles, or for other adjustment or regulation or cleaning of the burner. The globe holder 29 is held in its closed position by the latch pin 31. See Fig. X. This latch pin is held in engagement 45 by means of the coiled spring 32 supported in a suitable housing 33 on the inner side of the globe holder 29. This globe holder 29 is preferably made ornamental as it is substantially the only metal part exposed below the hangers or side members of 50 the frame.

The globe is open at the top and the lamp is entirely open above the globe holder. The globe holder in the structure illustrated 55 incloses the member 12 and also the pilot and the nozzle regulating valves, the stem of the valve 14 projecting over the same, so that its actuating lever 34 is outside of the globe holder as shown. The air inlets 35 of the mixing tube are adjacent to the periphery of the globe holder, but below the plane of the upper edge thereof.

The lamp, being entirely open above the burner and there being no operating or 60 metal parts to obstruct the passage of the

light rays upwardly around the burner through the skeleton frame, is therefore rendered practically shadowless. Also, as all the operating parts of the lamp and metal connections, the ornamental hanger members, the ornamental globe ring, together with the valves, burner tubes, and other operating parts are entirely outside of the path of the products of combustion, and therefore do not become heated enough to interfere with the successful operation of the lamp or enough to spoil the finish, and the products of combustion do not contact therewith sufficiently to tarnish. Further, owing 70 to the unobstructed center above the burner and the wide open globe or bowl, reflected light rays are communicated from the inner surface of the bowl over a wide area and the reflected heat rays are, to a large degree, distributed, as are the light rays. The lamp being fully open, the ascensional force of the 75 products of combustion from the burner is so greatly reduced as not to affect the ornamental top.

The lamp being entirely open above the 80 burner, causes a central upward current and draws fresh air to the burners to properly maintain combustion at that point and also to furnish a supply of fresh air to the ports 85 of the mixing tube. The burners thus 90 supported are well protected from drafts of air, the lamp, of course, being designed for inside lighting, and the parts are at the same time so constructed that none of them become unduly or excessively heated.

A further advantage is the ornamental feature of the lamp. By using an opaque or semi-opaque or translucent globe, the light is reflected upwardly, and, as stated, there are no parts to cast shadows, thus making a 105 highly desirable construction. My improved lamp is also desirable on account of the simplicity and economy of structure, and the ease with which it may be cared for.

I have illustrated and described my improved lamp in detail in the form in which I have embodied the same. I have not attempted to illustrate or describe certain modifications and details which I contemplate as I believe the disclosures made will 110 enable those skilled in the art to which this invention relates to embody or adapt the same as conditions may require.

Having thus described my invention, what I claim as new and desire to secure by Letters Patent is:

1. In a gas lamp, the combination with a valve casing, of a gas delivery nozzle on said casing, there being a mixing tube nipple on said valve casing, a horizontally disposed mixing tube on said nipple, a burner supporting arm, said valve casing being provided with a downwardly projecting supporting ear for said arm, and a burner having a horizontally disposed inlet passage 125

slidably engaged with said mixing tube and a downwardly projecting perforated ear engaged with said supporting arm.

2. In a gas lamp, the combination with a valve casing, a gas delivery nozzle on said casing, a horizontally disposed mixing tube mounted on said casing, a burner supporting arm on said casing, and a burner having a horizontally disposed inlet passage having a telescoping engagement with said mixing tube and engaged with said supporting arm.

3. In a gas lamp, the combination with the valve casing, a horizontally disposed mixing tube mounted on said valve casing, a burner supporting arm disposed below said mixing tube, and a burner having telescoping engagement with said mixing tube and engaged with said arm.

4. In a gas lamp, the combination of a skeleton frame consisting of a top member, side members depending from said top member, one of said side members being adapted as a gas delivery conduit, and a ring-like supporting member on the lower ends of said side member, and an inverted burner comprising a horizontally disposed mixing tube the width of the supporting member being approximately the diameter of the mixing tube.

5. In a gas lamp, the combination of a skeleton frame comprising a top member, side members depending therefrom, one of said side members being adapted as a gas delivery conduit, an annular supporting member on the lower ends of said side members, a burner comprising a horizontally disposed mixing tube, the width of said supporting member being substantially the diameter of said mixing tube, and a translucent globe open at its upper end embracing said burner from below.

6. In a gas lamp, the combination of a skeleton frame consisting of a top member, downwardly diverging side members depending from said top member, one of said side members being adapted as a gas delivery conduit, and an annular supporting member on the lower ends of said side members, an inverted burner mounted within said supporting member, a translucent globe open at its upper end, and an annular globe supporting ring mounted upon said supporting member and coacting with said globe to embrace said supporting member and the burner from below, whereby light may be reflected from the inside of the globe upwardly through said frame.

7. In a gas lamp, the combination of a supply pipe, a skeleton frame comprising a coupling member, mounted on said supply pipe, rod-like side members depending from said coupling member, one of said side members constituting a delivery conduit, and a narrow band-like supporting member on the lower ends of said side members, a burner, a

globe and a globe supporting band hinged upon said supporting member and adapted to close over and embrace the supporting member and the lower ends of said side members.

8. In a gas lamp, the combination of a supply pipe, a skeleton frame comprising a coupling member, mounted on said supply pipe, rod-like side members depending from said coupling member, one of said side members constituting a delivery conduit, and a band-like supporting member on the lower ends of said side members, a burner, a globe and a globe supporting band mounted upon said supporting member and embracing the supporting member and the lower ends of the side members.

9. In a gas lamp, the combination of a skeleton frame comprising a top member, side members depending therefrom, one of said side members being adapted as a gas delivery conduit, a valve casing mounted on the side member adapted as a gas delivery conduit, a burner mounted on said valve casing, a globe supporting means, a translucent globe open at its upper end disposed below said frame, said globe supporting means and globe embracing the lower ends of said side members, said valve casing, and said burner from below, whereby light may radiate from the burner and may be reflected from the inside of the globe upwardly through said frame.

10. In a gas lamp, the combination of a skeleton frame comprising a top member, side members depending therefrom, one of said side members being adapted as a gas delivery conduit, a burner carried by said side member adapted as a gas delivery conduit, a globe supporting means, and a translucent globe open at its upper end disposed below said frame, said globe supporting means and globe embracing the lower ends of said side members and said burner from below whereby light may radiate from the burner and may be reflected from the inside of the globe upwardly through said frame.

11. In a gas lamp, the combination of a skeleton frame comprising a top member, side members depending therefrom, one of said side members being adapted as a gas delivery conduit, an inverted burner supported at the lower ends of said side members and centrally thereof, a globe supporting means, and a translucent globe open at its upper end disposed below said frame, said globe supporting means and said globe embracing the lower ends of said side members and said burner from below whereby light may radiate from the burner and may be reflected from the inside of the globe upwardly through said frame.

12. In a gas lamp, the combination of a supply pipe, a skeleton frame comprising a coupling member mounted on said supply

- pipe, rod-like side members depending from said coupling member, one of said side members being adapted as a gas delivery conduit, a burner carried by said side member 5 adapted as a gas conduit, a globe supporting means, and a translucent globe open at its upper end, said globe supporting means and globe embracing the lower ends of said side members and said burner from below 10 whereby light may radiate from the burner and may be reflected from the inside of the globe upwardly through said frame.
13. In a gas lamp the combination of a supply pipe, a skeleton frame comprising a top member, side members depending therefrom, one of said side members being adapted 15 as a gas delivery conduit, a supporting member mounted on and embracing the lower ends of said side members, a burner, 20 and a globe supporting band mounted upon said supporting member.
14. In a gas lamp, the combination of a skeleton frame comprising a top member, depending side members, an annular supporting member mounted on the outer sides of the lower ends of said side members, and a burner disposed within said supporting member. 25
15. In a gas lamp, the combination of a skeleton frame comprising a top member, side members depending therefrom, one of said side members being adapted as a gas delivery conduit, a valve casing mounted on said side member adapted as a gas delivery 30 conduit, a burner mounted on said valve casing, a globe supporting means, and a translucent globe open at its upper end, said globe supporting means and globe embracing the burner and the lower ends of said 35 side members from below.
16. In a gas lamp, the combination of a top member, side members depending therefrom, one of said side members being adapted 40 as a gas delivery conduit, and an annular supporting member mounted on the lower ends of said side members, a burner mounted within said supporting member, and a translucent globe open at its upper end, said globe and supporting member embracing said 45 burner and the lower ends of said side members from below.
17. In a gas lamp, the combination of a skeleton frame comprising a top member, side members depending from said top member, one of said side members being adapted 50 as a gas delivery conduit, an annular globe supporting member mounted at the lower 55
- ends of said side members, an inverted burner disposed within said globe supporting member, the width of said globe supporting member being approximately the depth of the burner parts and a translucent globe open at the top embracing said burner from below there being an unobstructed passage for the light and the products of combustion upwardly around the burner between the members of said frame. 60
18. In a gas lamp, the combination of a skeleton frame consisting of a top member, side members depending from said top member, and an annular supporting member mounted on the lower ends of said side members, one of said side members constituting a gas delivery conduit, a burner disposed within said annular supporting member with its body portion in the plate thereof, and a translucent globe inclosing said burner from below, the burner mantles being supported centrally of the globe and below the upper edge thereof, there being an unobstructed passage for the light and the products of combustion upwardly around the burner through said skeleton frame. 70
19. In a gas lamp, the combination of a skeleton frame comprising a top member, an annular supporting member, and side members diverging downwardly from said top member to said supporting member, one of said side members constituting a gas delivery conduit, and a translucent globe embracing said burner from below, the passage of the light and the products of combustion around the burner between the side, top, and supporting members of said frame being unobstructed. 75
20. In a gas lamp, the combination of an inverted burner, a skeleton frame consisting of a top member and depending side members, one of said side members being adapted as a gas delivery conduit, a burner disposed at the lower end of said frame, and a translucent globe open at its upper end disposed below said frame to embrace said burner from below, there being an unobstructed passage for the light and the products of combustion upwardly around said burner and between the members of said frame. 80
- In witness whereof, I have hereunto set my hand and seal in the presence of two witnesses.
